VIRGIL PRICE, OF NEW YORK, N. Y.

Design No. 4,265, dated July 26, 1870.

DESIGN FOR A SWORD-GUARD.

The Schedule referred to in these Letters Patent and making part of the same.

To all whom it may concern:

Be it known that I, VIRGIL PRICE, of the city of New York, in the county and State of New York, have invented a new and original Design for Sword-Guards; and I do hereby declare that the following is a full, clear, and exact description thereof, which will enable others skilled in the art to make and use the same, reference being had to the accompanying drawing forming part of this specification.

This invention relates to a new design for sword-guard and is fully illustrated in the drawing.

The design consists of three main parts, the central shield *a*, the arms *b b*, and the end shields *c c*.

The central shield is of quadrangular or other suit-

able form, and arched, as indicated by the shading in the drawing.

A plain or ornamental molding serves to decorate the edge of this shield.

The arms *b b* are decorated with ornamental relief borders *e e*, which are fully shown.

The end shields *c* are of oval or other suitable form, and have plain or ornamental borders *f*.

I claim as my invention—

The design for sword-guards, as shown.

VIRGIL PRICE.
